P.C.(57) **CLAIM**

The ornamental design for a vehicle seat, as shown and described.

DESCRIPTION

FIG. 1 is a front, top and right side perspective view of a vehicle seat showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an enlarged fragment view taken along line 8-8 in FIG. 2 thereof; and,

FIG. 9 is a cross-sectional view taken along line 9-9 in FIG. 8.

The dash-dot-dash broken lines represent the boundary lines of the claimed design.

The lightweight dashed broken lines shown in the drawings outside of the dash-dot-dash boundary lines represent portions of the vehicle seat that form no part of the claimed design.

The heavyweight dashed broken lines shown in the drawings within the dash-dot-dash boundary lines illustrate stitching and do form a part of the claimed design.
